DESIGN FOR A TOILET HINGE

Dudley S. Warth, Longmeadow, Mass.

Substituted for abandoned application Serial No.
83,724, March 21, 1939. This application January 22, 1940, Serial No. 89,633

Term of patent 7 years

To all whom it may concern:

Be it known that I, Dudley S. Warth, a citizen of the United States, residing at Longmeadow, in the county of Hampden and State of Massachusetts, have invented a new, original, and ornamental Design for a Toilet Hinge, of which the following is a specification, reference being had to the accompanying drawing, forming a part thereof.

This application is a substitute for application Serial No. D-83,724 filed on March 21, 1939.

Fig. 1 is a perspective view of a toilet hinge showing my new design;

Fig. 2 is a front elevation of the same;

Fig. 3 is a side elevation of the hinge; and
Fig. 4 is a section taken on the line 4—4 of
Fig. 2.

I claim:

The ornamental design for a toilet hinge, substantially as shown.

DUDLEY S. WARTH.
